US0D1073419S

(12) **United States Design Patent** (10) **Patent No.:** **US D1,073,419 S**
(45) **Date of Patent:** **** May 6, 2025**

(54) **PLANTING DEVICE**

(71) Applicant: **CIXI HUAZHIJIE PLASTIC PRODUCT CO., LTD.**, Zhejiang (CN)

(72) Inventors: **Jie Hua**, Zhejiang (CN); **Shimin Hua**, Zhejiang (CN)

(73) Assignee: **CIXI HUAZHIJIE PLASTIC PRODUCTS CO., LTD.**, Zhejiang (CN)

(**) Term: **15 Years**

(21) Appl. No.: **29/897,342**

(22) Filed: **Jul. 13, 2023**

(30) **Foreign Application Priority Data**

Jun. 6, 2023 (CN) 202330343926.0

(51) **LOC (15) Cl.** **08-01**

(52) **U.S. Cl.**

USPC **D8/1; D8/7**

(58) **Field of Classification Search**

USPC D8/1, 7, 9, 10, 11

(57) **CLAIM**

The ornamental design for a planting device as shown and described.

DESCRIPTION

FIG. 1 is a first perspective view of a planting device showing our new design;

FIG. 2 is a second perspective view thereof;

FIG. 3 is a front view thereof;

FIG. 4 is a rear view thereof;

FIG. 5 is a left view thereof;

FIG. 6 is a right view thereof;

FIG. 7 is a top view thereof;

FIG. 8 is a bottom view thereof; and,

FIG. 9 is a perspective view of the planting device of FIG. 1 in a using state.

The broken lines in the drawings illustrate portions of the planting device and form no part of the claimed design.

1 Claim, 8 Drawing Sheets
